United States Patent Office.

WILLIAM E. CATLIN, OF WAYNE TOWNSHIP, PENNSYLVANIA.

Letters Patent No. 68,287, dated August 27, 1867.

MUSICAL SCALE.

The Schedule referred to in these Letters Patent and making part of the same.

TO ALL WHOM IT MAY CONCERN:

Be it known that I, WILLIAM E. CATLIN, of Wayne township, in the county of Erie, and State of Pennsylvania, have invented a new and useful diagram, which I call the Transposition Teacher, for the better illustration of the transposition of the Musical Scale; and I do hereby declare that the following is a full, clear, and exact description of the construction and operation of the same, reference being had to the annexed drawings, making a part of this specification.

This "transposition teacher" may be made of paper, pasteboard, tin, or anything that can be used in like manner, and of all sizes, from the pocket size to a size suitable to suspend in the singing-class room.

I construct my "transposition teacher" of two pieces. The first is a wrapper, as shown in the drawings by the Figures one, one, (1, 1,) &c., which is a piece of pasteboard or other material, cut twice the width of the "teacher," and enough wider to turn in to the sectional line shown at Figure three, (3,) thus keeping in its place the second piece of the "teacher," which is a slide made of the same material, and only one thickness, cut to slide easily within the wrapper, and of the same length as the wrapper, as shown by the blue lines in the drawings at Figure two, two, (2, 2,) &c. Upon both sides of the wrapper, alike, I place the musical scale, so as to represent fully all the half-steps of the staff instead of simply the places of the letters, as on the staff in common use, which shows no distinction between the half-step and the whole-step intervals between the letters of the staff. I represent the lines of the common staff by the heavy lines in the drawings, upon which stand the letters E, G, B, D, and F. I represent the spaces by the lighter lines F, A, C, and E; and the sections of lines at Figures four, four, (4, 4,) &c., represent the half-steps not shown in the common scale, and which occur in the whole-step intervals between the letters of the staff. In the left end of the common scale I cut an oblong place, as shown by the lines marked by Figures five, five, (5, 5;) and in the right end of the wrapper I cut an oblique place, as by lines at Figures six, (6, 6.) On one side of the slide I place the flats, near the left, and near the right end the sharps, as used in transposition by the flats, the key-notes underlined with short dark lines, and the rest underlined by short red lines, to distinguish them the quicker, and in such a manner that the "teacher," when closed, represents the natural scale, or key of C natural, on both sides alike, with no flats or sharps in sight, and syllables to match. By drawing the slide to the right we have on the side shown in the drawings, first, the appearance of one, two, &c., flats, through the opening of the wrapper at figs. five; and then the corresponding changes in the key-note and syllables appear through the opening in the wrapper at figs. six, which, by the aid of the representation of all the half-steps of the scales, solves at a glance, for the scholar, the obscurity which attends the teaching of the transposition of the musical scale without the illustration that my invention gives.

I fasten the parts of the teacher together with two pieces of ribbon, as shown by Figures eight, (8,) passed through two slits in the wrapper and through an oblong place cut in the slide, shown by Figures seven, (7,) which secures the slide and allows it to be moved far enough only to show all the changes by the transpositions shown thereon. In the drawings the slide is drawn out to its full extent for illustration, and makes all the flats visible through the opening in the wrapper at five, while a portion of the wrapper, from the figs. six to the right end, is shown as torn away to show the key-notes and syllables as written on the slide. On the opposite of the teacher are placed the sharps in like manner, with syllables, &c., to correspond; and all their respective changes are shown in like manner, at the same time, by the same movement of the slide. X is a place cut away from the end of the wrapper to admit of catching the slide with the thumb and finger.

What I claim as my invention, and desire to secure by Letters Patent, is—

The construction and use of my "transposition teacher," as and for the purpose set forth.
